Dressing Stone.

No. 95238.

Patented, Sep 28, 1866.

UNITED STATES PATENT OFFICE.

T. H. LEAVITT, OF BOSTON, MASSACHUSETTS.

IMPROVED MACHINE FOR DRESSING STONE.

Specification forming part of Letters Patent No. 95,238, dated September 28, 1869.

To all whom it may concern:

Be it known that I, T. H. LEAVITT, of Boston, in the county of Suffolk and State of Massachusetts, have invented an Improvement in Machinery for Grinding, Dressing, or Reducing Stone; and I do hereby declare that the following, taken in connection with the drawing which accompanies and forms part of this specification, is a description of my invention sufficient to enable those skilled in the art to practice it.

My invention relates particularly to an organization of mechanism for grinding or dressing stone, the improvements being, however, applicable in whole or in part to machines for grinding, surfacing, or dressing other material.

The invention consists primarily in combining with a reciprocating table or carriage moving upon horizontal ways or rails a rotary grinder cylinder or disk, the grinding-surface of which is made up of a series of segmental, sectoral, or annular blocks, made capable of adjustment or of displacement and replacement, so that such changes may be readily made as are required by the nature of the material to be ground, the figure to be produced, or the wear of the tools. These grinding-surfaces do not in themselves reduce the material, but are the carriers or vehicles by which abrasive powder, paste, or granulated abrasive matter is held to and ground against the stone or other material, which, by the action of the abrader (produced by the movement of the carriers) is brought to a plane or irregular form corresponding to the form of the acting surfaces of the carriers.

The invention also consists in certain details of mechanism chiefly auxiliary to the employment of these sectional rotary grinders or laps.

The drawing represents a machine embodying my improvements.

A shows the machine in side elevation. B is an end view thereof.

a denotes the frame upon ways or rails, at the top of which rests and slides the horizontal reciprocating carriage or table c, that supports the material to be dressed, the longitudinal movements of the carriage being imparted by any suitable mechanism. At the opposite sides of the frame a are uprights d, between which is located the rotary grinder or lap, which forms the vehicle for applying the surface-reducing abrader. This lap may be either

a cylinder, as seen at e, mounted upon a horizontal shaft, f, or a disk, as seen at g, at the foot of a vertical shaft, h, and, whether one or the other, it is composed of a series of sectional pieces, the outer surfaces of which form the carriers for presenting the abrader. The cylinder-carrying shaft f is journaled in bearings i, sliding in the uprights d, said bearings being supported on vertical screw-shafts k, turning in bearings in the posts d, the shafts being simultaneously rotated by a cross-shaft, l, carrying bevel-gears m, meshing into and driving bevel-gears n on the upper ends of the two screw-shafts. By these means the cylinder is lowered as the surface of the stone is ground away by it. The disk is raised and lowered by analogous means, its shaft being journaled in bearings at the center of cross-beams, the opposite ends of one or both of which carry nuts or boxes worked by vertical screw-shafts, having gears driven by gears upon a cross-shaft.

The cylinder e is driven by suitable gearing connecting its shaft to the main shaft o, and the cylinder is constructed as follows: Between two heads, p, located on the shaft, I place a pulley, r, made whole or of a series of narrow pulleys or collars, and over this cylinder I slip a series of grinder-rings, each made up of segmental blocks s, each of which has a series of holes through which pass long bolts t, extending from head to head, the adjacent segments being clamped tightly together by means of these bolts. Each segment-formed ring corresponds in inner diameter to the diameter of the cylinder e, and their outer diameters are the same, so that when bolted together they form a grinding-cylinder of uniform diameter throughout, so far as relates to the respective sections composing the cylinder. One end of the outer curved surface of each segment may retreat from the cylindrical grinder surface, as seen at u, forming between the adjacent ends of each two adjacent segments a slight recess, which will take up the abrasive powder as the cylinder rotates.

The grinder-blocks may be made of an suitable material adapted to presenting an rubbing the abrader against the surface to be reduced; wood, metal, leather, or other material being employed, according to the nature of the material to be worked or the surface to be produced. The bolt-holes in the block

may be slotted to permit slight adjustments of the grinder-surfaces.

When a series of collars are used to form the segment-carrying cylinder they are preferably made of widths varying from the widths of the segments, so as to break joints between the segments and collars. The cylinder being thus constructed, and a block or slab of stone to be reduced being placed and fastened upon the carriage, and the cylinder being fed down to the plane of the surface of the stone, the cylinder and bed are set in motion, and sand, emery, or other abrasive material and water being then fed to the surface of the cylinder, the surface of the stone will be rapidly and uniformly reduced to a practically - perfect plane.

For conducting the abrasive agent and the water to the cylinder a mechanism may be used as follows: The abrader is placed in a hopper or reservoir, r , at the bottom of which may be a screen for keeping back the coarse grains or particles. This hopper discharges at bottom into the top of a chute or conductor, w , which extends down at the front of the cylinder, the bottom of the chute being formed into a long narrow discharge-slit extending the length of the cylinder, and discharging the powder entirely across the same. To guide the powder to a portion of the length of the slit I use guides x , hung on pins y , by means of which each may be swung toward or from the adjacent side of the chute, and just under the bottom of the hopper or at the top of the chute I place valves z , by turning which the amount of powder delivered into the chute may be regulated as circumstances may render desirable. Between the hopper and the cylinder is a trough, a^2 , extending the length of the cylinder and pierced at bottom with holes b^2 . Into this trough water or other liquid is let from any convenient source of supply, and through the holes the water percolates and drops upon the cylinder, mingling with and moistening the sand supplied from the hopper. The water may be let directly into the hopper and run through with the sand; but the arrangement shown I consider preferable.

The disk grinder (the flat surface of which is presented to the stone in grinding) is constructed as follows:

g denotes a circular head or disk fixed upon the foot of the vertical shaft h . The bottom of the head is provided with a series of sectoral grinder-blocks, c^2 , the two radial edges of each of which may have tongues d^2 , fitting under lips e^2 on radial strips f^2 , fixed to the under side of the head. When in position the circular edge of each sector projects out beyond the periphery of the head, except at the upper corner, where the edge retreats to a line corresponding with the periphery of the head, and a hoop or band, g^2 , slipped over the periphery, drops down around the sectors and rests on top of their projecting edges, thereby confining the sectors in position. At the center of the head is a receiver, h^2 , into the top of

which the sand or other abrading material is conducted from a hopper, i^2 . This receiver discharges the abrader into a series of conductors or passages, j^2 , leading through the disk and into a common axial passage, k^2 , as seen at C, from which passage the sectors radiate, as seen at D, the sand or abrading powder and water running through the hopper and conductors down upon the stone and being thrown laterally between the adjacent sectors by centrifugal force and taken up by the several sectors, one edge of each of which may be inclined, as seen at D, the better to take the sand.

The hopper may be provided with a screen to keep back the too-coarse particles of the abrasive agent.

The disk may be also provided with a series of holes, l^2 , running through it and disposed radially, as seen at D, sand and water passing through these holes from the top of the disk, being delivered between the sectors, each series of holes being between two sectors; and to prevent the sand from being thrown from the top of the disk by centrifugal force, the disk may have an upturned peripheral flange, m^2 , as seen at C.

The cylinder grinder and the disk grinder may be used together in grinding plane faces of stone or other material during the reciprocatory movements of the carriage, or either may be used alone; but, besides their adaptation to produce such plane surfaces, each may be used in producing moldings, fluted or beaded work, the cylinder to produce straight work of this kind, and the disk circular or sections of circular work. For this purpose each segmental grinder-block on the cylinder will have a peripheral grinding-edge the converse of the surface to be produced upon the stone or other material as it is fed under the cylinder, as seen, for instance, at E, F, and G; and for circular work the face of each grinder-sector will have a form in radial section corresponding in form to a corresponding section of the circular work to be produced, as will be readily understood, the stone being of course held still while the rotating disk-sectors are operating, a section of one of such sectors being shown at I.

A long pillar, cylinder, or column may be fluted, grooved, or polygonally faced by the cylinder grinder by mounting it between suitable heads at opposite ends of the carriage on center points, dogging the work in stationary position relatively to the carriage, the carriage being then reciprocated as in grinding plane and wide surfaces. After each groove, bead, or polygonal face is formed the column is turned upon its centers to bring it into position for the formation, in the same manner, of the next groove, flute, bead, or face.

For producing the curved surfaces of building stone for "swell fronts" I use an auxiliary table or carriage, similar to that shown at H, upon the under surface of which are curved cross-pieces n^2 , which rest and slide upon

curved transverse rails o^2 . The under surface of the bed has fixed upon it circular gear-racks p^2 , which engage with the teeth of pinions q^2 on a shaft, r^2 . This carriage is mounted upon the table or carriage c , the blocks being laid crosswise of the auxiliary table, (the surfaces to be reduced uppermost,) and the surfaces over the center of the table being reduced (under the rotary movements of the grinders and the longitudinal movements of the carriage) down to a surface tangential to the curve to be formed. The shaft r^2 is gradually rotated in each direction, causing the table to slide on the curved rails and reducing the surfaces of all the blocks to a corresponding or concentric curve.

At the opposite sides of the table or carriage c , I place troughs s^2 , the tops of which (adjacent to the bed) are on a plane with the surface of the bed, so that all water and semi-fluid matter (made up of water, the material ground off from the stone, and the abrader) escaping from the bed, will pass off of the carriage into the troughs, from whence this watery and semi-fluid matter may be drawn off by suitable conduits, this provision not only keeping the frame-work and mechanism of the machine dry and in good condition, but also keeping all the space about the machine clean and neat.

Each sand-containing hopper is placed upon a suitable stand or frame, t^2 , over the grinder, and to preserve the relative distance between the grinder and hopper, this frame may be supported upon boxes or nuts u^2 , the screw-threads of which rest against the adjacent screw-shafts, so that the same vertical movements imparted to the grinder and also imparted to the hopper.

By means of a grinding mechanism organized to operate as shown and described work may be very cheaply performed, the sectional grinders or laps may be readily renewed as they become worn, one kind of grinder may be easily substituted for another, a very great variety of work can be accomplished in the same machine with interchangeable devices, and the machine is enduring, and is simple in construction and operation.

When the cylinder and the disk grinder

operate at the same time in reducing or surfacing a stone to a flat surface it will be obvious that any tendency of the cylinder to make grooves upon the stone or to grind the surface irregularly is corrected by the disk grinder, which works laterally over the surface of the stone, while each portion or segment of the cylinder works longitudinally with respect thereto.

I claim—

1. In a machine for dressing stone, having a reciprocating work-supporting table or carriage, a horizontally-axed grinding-cylinder, the grinding-surface of which is composed of a series of peripheral segments bolted together and confined between the cylinder-heads, substantially as described.

2. A horizontal disk grinder composed of sectoral blocks fastened to the lower face of a rotary head fixed to the foot of a vertical shaft, the sectors being so confined in position that any one or more may be removed for repairs or replacement.

3. In a grinding-machine having a reciprocating work-supporting table or carriage, the combination of a cylinder grinder rotating on a horizontal axis, with a disk grinder at the foot of a rotary vertical shaft, substantially as shown and described.

4. In a stone-dressing machine, a reciprocating carriage having long side troughs for receiving the liquid and semi-liquid matter escaping from the stone, the troughs being fixed to or forming part of the table.

5. In combination with the sand-receiving hopper, a chute or conductor so constructed and arranged as to convey the sand to the whole length of the grinding-cylinder, and having provision for controlling and regulating the feed of the sand.

6. In combination with a reciprocating work-supporting table or bed, mounting the bed upon curved rails or ways for lateral curvilinear movement, substantially as and for the purpose described.

T. H. LEAVITT.
